CLOSURE SECURING RING

Charles Sabatt and Daniel F. Manion, Jr., Oil City, Pa., assignors to Rouseville Cooperage Company, Rouseville, Pa., a corporation of Pennsylvania

Application March 31, 1939, Serial No. 265,220

3 Claims. (Cl. 220—61)

This invention relates to improvements in split rings such as are employed in connection with receptacle closures and which are adapted, when contracted, to secure the closures in place and when expanded to release them so that they may be removed.

One object of the invention is to provide a ring for the purpose described which may be adjusted with facility to fit receptacles of different sizes.

10 A further object is to provide a ring which, when contracted, may be locked in such a manner as to insure against its accidental or unintentional release.

The invention is illustrated in the accompanying drawings in which:

Figure 1 is a top view of a steel drum having its closure secured in place by a ring embodying the features of the invention.

20 Figure 2 is an enlarged fragmentary view and is taken along line 2—2 of Figure 1.

Figures 3, 4, 5 and 6 are enlarged sections taken along lines 3—3, 4—4, 5—5 and 6—6, respectively, of Figure 2.

25 Figure 7 is a horizontal section taken along line 7—7 of Figure 2 and illustrates the positions of the parts when the ring is initially adjusted, as in Figure 2, to increase its diameter.

Figure 8 is a similar view showing the relation of the parts when the ring is partially contracted.

30 Figure 9 is a view similar to Figure 2 illustrating the positions of the parts when the ring is initially adjusted to decrease its diameter.

Figure 10 is a section similar to Figure 7, the ring in this instance, however, being adjusted 35 to the size shown in Figure 9.

Figure 11 is a similar view showing the relation of the parts when the ring is partially contracted.

The receptacle with which the ring is illustrated, by way of example, is of the steel drum type, being suitably indicated for the purpose in view by a showing of the side wall 15 (Figure 3) and the annular outwardly rolled bead 16 which is formed around the top edge thereof. The cover is indicated at 17 and, as is conventional, 40 is formed with a body portion which fits in the open end of the receptacle and a peripheral flange 18 which overlies, and conforms generally to the shape of, the bead 16, a gasket 19 being arranged between the flange and the bead to 45 provide a seal.

The ring, indicated at 20, is U-shaped in cross section, is split and is contractable. The free ends thereof terminate in spaced relation and, in accordance with the invention, carry dependent 50 extensions 21 and 22 which are formed to

provide channels 23 and 24 respectively. A link 25 is pivotally connected by a pin 26 (Figure 4) to each of the walls of the channel 23, the free ends of the two links being connected by a cross-pin 27 (Figure 5) to which the forked end of a 5 lever 28 is connected. A pin 29 (Figure 4) connects the forked end of the lever to one end of a link 30, the other end of the link being pivotally connected to a pin 31 (Figures 2 and 6) which is mounted between the walls of the channel 24. 10 When the lever 28 is moved to an extended position, that is to say outwardly with respect to the center of the ring, it is operative to spread the ends of the ring to increase its diameter, thereby to enable it to be applied or removed 15 from the receptacle. On the other hand when the lever is moved to its retracted position, i. e. toward the center of the ring to a position in which it is arranged under the bead 16 and alongside the wall 15, it is operative to contract 20 the ring, it being apparent that when the ring is arranged over the cooperating flange and bead of the cover and drum, respectively, and contracted the gasket 18 will be compressed to seal the cover upon the drum. In this connection it 25 will be noted that the link 30 has an inwardly extending end which is connected to the lever 28. Clearance between it and the cross-pin 27 is thus provided when the lever is in its retracted 30 position.

It will be noted that the links 25 are adjustable through an angle of approximately 180° to one position (Figure 8) in which the cross-pin 27 is located at one side of the pivot pins 26 and to a second position (Figure 11) in which the cross-pin is located at the opposite side of the pivot pins. The links, in other words provide two positions of pivotal support for the lever 28, it being apparent that movement of the cross-pin to the first position increases the distance between the ends of the ring, and hence increases its diameter while movement of the cross-pin to the second position decreases the distance between the ends of the ring, and hence decreases its diameter. The adjustments described 40 are made while the lever is in its extended position. They are for the purpose of initially correcting the diameter of the ring and enable it to be fitted to different sizes of receptacles. After such adjustments have been made the lever 28 is moved to its retracted position to contract the ring and thereby apply the requisite amount of pressure to the cover.

In order to lock the lever against its accidental or unintentional release after it is moved to its 55

retracted position for the purpose described, the side walls of the channel 23 are formed with aligned openings 32 (Figure 4) for accommodating a tapered pin 33. The openings 32 are located 5 at one side of the pivot pins 26 and when the links 25 are adjusted to increase the size of the ring, the pin 33 may be inserted through the openings in front of the links 25 and the lever 28 to lock the parts against return movement, the link 30 being notched as indicated at 34 (Figure 8) to provide clearance for the pin. Preferably 10 a seal 35 is employed to secure the latter in the position described. The pin 33 also serves to lock the parts against return movement when 15 the ring is contracted with the links 25 occupying their other position of adjustment (see Figures 10 and 11). In this case the pin is inserted through a hole 36 which is formed in the link 30 and which is moved into alignment with the 20 openings 32.

The free end of the lever 28, as best shown in Figure 2, is tubular and is adapted, when the lever is in its fully retracted position, to accommodate a rod 37. The latter is mounted for 25 lengthwise movement at the underside of the ring in spaced guides 38 which are in the form of depending straps and provides a supplemental locking means. It insures against play of the free end of the lever and may be employed in 30 connection with or independently of the pin 33. The wire of a seal 39 may, if desired, be inserted through suitable openings in the rod at opposite sides of one of the straps 38, as illustrated, to prevent its accidental or unintentional withdrawal from the end of the lever.

I claim as my invention:

1. A ring for removably securing a cover upon a receptacle, said ring being split and having the adjacent ends spaced apart, a lever which 40 is movable to a retracted position to contract said ring, the inner end of said lever terminating in a fork, a pair of parallel spaced-apart links between which the terminal portions of the branches of said fork extend, each of said links 45 having one end pivotally connected to one end of said ring, the other end of one of the links being pivotally connected to one of the branches of said fork and the corresponding end of the other of said links being pivotally connected to 50 the other of said branches, a third link having one end extending between and pivotally connected to the branches of said fork in spaced relation with respect to the pivotal connections of said branches with said links and the other end of said link being pivotally connected to the other end of said ring, the connections of 55 the branches of said fork with said pair of links providing a pivotal axis about which said lever is moved to contract said ring, said links being adjustable about their connections with said first 60 mentioned ring and to pre-locate said pivotal axis at either side of said last named connections at substantially the same distance from the common axis of the receptacle and ring, whereby the degree of contraction effected by said lever may be varied by adjusting said pair of links to either of the positions described prior to the operation 65 of the lever and means for locking said lever in its retracted position.

2. A ring for removably securing a cover upon a receptacle, said ring being split and having the adjacent ends spaced apart, depending lugs carried by said ring ends, one of said lugs being channel-shaped and having spaced horizontal walls, a lever which is movable to a retracted position to contract said ring, the inner end of said lever terminating in a fork, a pair of parallel spaced-apart links located between the walls of said last mentioned lug and between which the 10 terminal portions of the branches of said fork extend, one of said links having one end pivotally connected to one of the horizontal walls of said lug and the other end pivotally connected to one of the branches of said fork and the other of said links having one end pivotally connected to the other of said horizontal walls and the other end pivotally connected to the other of said branches, a third link having one end extending between and pivotally connected to the branches of said 15 fork in spaced relation with respect to the pivotal connections of said branches with said links and the other end of said link being pivotally connected to the other of said lugs, the connections of the branches of said fork with said pair of links providing a pivotal axis about which said lever is moved to contract said ring, said links being adjustable about their connections with said first mentioned lug to pre-locate said pivotal axis at either side of said last named connections 20 at substantially the same distance from the common axis of the receptacle and ring, whereby the degree of contraction effected by said lever may be varied by adjusting said pair of links to either of the positions described prior to the operation 25 of the lever and means for locking said lever in its retracted position.

3. A ring for removably securing a cover upon a receptacle, said ring being split and having the adjacent ends spaced apart, said ends being provided with depending portions, a lever which is movable to a retracted position below said ring to contract the latter, a link having one end pivotally connected to one of said depending portions and the other end pivotally connected to the inner end of said lever, a second link having one end pivotally connected to said lever in spaced relation with respect to said inner end and the other end pivotally connected to the other depending end portion, the connection of said first mentioned link with said lever providing a pivotal axis about which said lever is moved to contract said ring, said first mentioned link being adjustable about its connection with said first mentioned depending ring portion to pre-locate said pivotal axis at either side of said last named connection at substantially the same distance from the common axis of the receptacle and ring, whereby the degree of contraction effected by said lever may be varied by adjusting said pair of links to either of the positions described prior to the operation of the lever, the adjustment of said first mentioned link in the manner described providing two different circumferential positions 55 of retraction of said lever and means for locking said lever in either of said positions.

CHARLES SABATT.
